(57) **CLAIM**

The ornamental design for a shoe strap, as shown and described.

DESCRIPTION

FIG. 1 is a front top right perspective view of a shoe strap.
FIG. 2 is a front elevation view of the shoe strap.

FIG. 3 is a rear elevation view of the shoe strap.

FIG. 4 is a right side elevation view of the shoe strap.

FIG. 5 is a left side elevation view of the shoe strap.

FIG. 6 is a top plan view of the shoe strap.

FIG. 7 is a bottom plan view of the shoe strap.

FIG. 8 is a rear top left perspective view of the shoe strap.

FIG. 9 is a front top right perspective view of an insert portion of the shoe strap in a different configuration with the remainder of the shoe strap removed for illustration purposes.

FIG. 10 is a front elevation view of the insert portion of the shoe strap in a different configuration with the remainder of the shoe strap removed for illustration purposes.

FIG. 11 is a rear elevation view of the insert portion of the shoe strap in a different configuration with the remainder of the shoe strap removed for illustration purposes.

FIG. 12 is a right side elevation view of the insert portion of the shoe strap in a different configuration with the remainder of the shoe strap removed for illustration purposes.

FIG. 13 is a left side elevation view of the insert portion of the shoe strap in a different configuration with the remainder of the shoe strap removed for illustration purposes.

FIG. 14 is a top plan view of the insert portion of the shoe strap in a different configuration with the remainder of the shoe strap removed for illustration purposes; and,

FIG. 15 is a bottom plan view of the insert portion of the shoe strap in a different configuration with the remainder of the shoe strap removed for illustration purposes.

The broken lines in the drawings depict portions of the shoe strap that form no part of the claimed design.

1 Claim, 9 Drawing Sheets
